UNITED STATES PATENT OFFICE.

ULRICH REIDT, OF LOS ANGELES, CALIFORNIA.

PERMUTATION-PADLOCK.

1,141,827.

Specification of Letters Patent. Patented June 1, 1915.

Application filed February 12, 1914. Serial No. 818,427.

To all whom it may concern:

Be it known that I, ULRICH REIDT, a subject of the Emperor of Germany, residing at Los Angeles, in the county of Los Angeles 5 and State of California, have invented certain new and useful Improvements in Permutation-Padlocks; and I do hereby declare the following to be a full, clear, and exact description of the invention, such as will 10 enable others skilled in the art to which it appertains to make and use the same.

My invention relates to new and useful improvements in permutation pad locks and resides in the provision of a lock which is 15 simple, reliable and efficient and cheap to manufacture.

An important object of my invention is to provide a lock of the character described which employs a novel form of locking 20 means which is simple as to construction, reliable and expeditious in operation and which may be cheaply manufactured.

The above and additional objects are accomplished by such means as are illustrated 25 in the accompanying drawings, described in the following specification and then more particularly pointed out in the claims which are appended hereto and form a part of this application.

With reference to the drawings, wherein 30 I have illustrated the preferred embodiment of my invention as it is reduced to practice, and throughout the several views of which similar reference numerals designate corresponding parts: Figure 1 is a view in elevation of the lock showing one of the sides of the lock casing removed, Fig. 2 is a sectional view taken on line 2—2 of Fig. 1, Fig. 3 is a top plan view, Fig. 4 is a fragmentary 40 detail sectional view of a portion of the locking means forming a part of the invention. Fig. 5 is a fragmentary side elevation with the plate removed partly in section.

Referring to the drawing the numeral 1 45 designates as an entirety a lock casing in which is mounted a sliding shackle 2. This casing 1 is provided with the usual removable side wall 3 that is secured by bolts or other suitable fastening means. One end of 50 the shackle 2 is longer than the other and has rotatably mounted thereon a cylindrical sleeve 4 which is provided at its ends with annular flanges 5 and 6. The longer end of the shackle 2 is reduced to provide 55 a shoulder 7 that is disposed adjacent the free end of the shackle. The sleeve 4

is reduced at its lower end to provide a shoulder 8 arranged to coöperate with the shoulder 7 to prevent upward movement of the sleeve upon the shackle 2. The extreme 60 end of the shackle may be enlarged to prevent downward movement of the sleeve 4. An outwardly extending annular flange 9 is formed on the sleeve 4 adjacent but spaced from the lower end thereof. This flange 9 65 is provided with a recess 10 which terminates inwardly at the curved face of the sleeve, and is for a purpose to be later described. An opening 12 is formed in the sleeve 4 and is adapted for registration with 70 a recess or indentation 13 that is formed in the shackle 2 in that part which is incised within the sleeve 4. The flange 6 on the lower end of the sleeve 4 rests in engagement with a flange or shelf 14 carried 75 by the casing as will be clearly seen with reference to Fig. 1 in the drawings.

Mounted centrally of the lock casing 1 adjacent the upper portion thereof is a pair of arcuate plates 15 and 16 that are pivoted 80 centrally of their ends as at 17. Pivoted between the plates 15 and 16 at the inner end thereof is a bolt 18 that is slidable through a suitable guide 19 and arranged to extend through the opening 12 in sleeve 4 85 into the recess or indentation 13 of the shackle 2. Thus it is seen that one end of the shackle 2 is adapted to be locked against removal from the casing 1. Pivoted between the plates 15 and 16 adjacent the other ends 90 thereof is a bolt 20 that is slidable through a suitable guide 21 and arranged to fit within a recess or indentation 22 formed in the adjacent end of the shackle 2. As a means for holding these plates 15 and 16 in such 95 a position that the bolts 18 and 20 are normally in extended or locked position there has been provided a leaf spring 23 that is secured in any suitable manner at one end as at 24, passes through a suitable guide 25 100 and engages at its free end one face of the plates 15 and 16 thus holding the bolts 18 and 20 in extended position.

Assuming that the shackle 2 is locked at both ends as illustrated in Fig. 1, to unlock 105 the shackle the sleeve 4 is so turned that the opening 12 therein is moved away from the bolt 18. In this connection it will be noted that the bolt 18 is beveled upon its side faces and top so that a reduced end is provided. 110 Upon engagement of the edge of the opening 12 in the sleeve with the adjacent bev-

eled face of the bolt 18, which face acts as a cam, the bolt will be moved outwardly relative to the opening 13 in the shackle and cause the bolt 20 to be moved out of locking engagement. Rotation of the sleeve is continued until the recess 10 in the flange 9 is in alinement with the end of the bolt when the shackle 2 is free to be moved outwardly from the casing 1 since at the time of the 10 moving of the opening 12 in the sleeve 4 from the bolt 18 the inward movement imparted to the bolt is sufficient to withdraw the bolt 20 from engagement with the shackle 2. Thus the shorter end of the shackle may be 15 withdrawn from the lock casing 1 and the unlocking is provided. The bolt 18 engages the flange 6 and prevents withdrawal completely of the shackle 2. It is found preferable to form the indentations 13 and 22 in 20 the nature of notches thus permitting a snug fitting and proper release.

It will be readily observed with reference to the foregoing description and accompanying drawings that I have provided a simple 25 and efficient form of lock which may be manufactured cheaply.

The extended portion of the sleeve 4 is provided with suitable characters or graduations arranged to correspond with an arcuate arrangement of graduations that are disposed upon the upper or adjacent face of the lock casing 1. These characters may be arranged as desired so that it will be necessary to impart a series of turns to the sleeve 30 before the desired locking or unlocking action is provided.

In reduction to practice, I have found that the form of my invention, illustrated in the drawings and referred to in the above 40 description, as the preferred embodiment, is the most efficient and practical; yet realizing that the conditions concurrent with the adoption of my device will necessarily vary, I desire to emphasize the fact that various 45 minor changes in details of construction, proportion and arrangement of parts may be resorted to, when required, without sacrificing any of the advantages of my invention, as defined in the appended claims.

50 What is claimed is:—

1. A lock comprising a casing, a shackle 55 slideable therein, a sleeve rotatably journaled upon one terminal of said shackle and dis-

posed for its greater length within the casing, said shackle having notches adjacent each end, said sleeve having an opening therein arranged to communicate with the notch in the adjacent end of said shackle, an annular flange formed on said sleeve adjacent to the opening therein and being provided with a recess, an annular flange formed on the extreme inner end of said sleeve, bolts pivoted within the casing and adapted for registration with the notches in said shackle, one of said bolts being arranged to bear upon the upper face of the flange that is arranged adjacent to the opening in said sleeve when said sleeve is rotated and spring means for normally holding said bolts in extended position. 70

2. A lock comprising a casing, a shackle slideable in said casing, a sleeve rotatably journaled upon said shackle and disposed partly within said casing and having an opening therein intermediate its ends, an annular flange thereon adjacent to the opening, a recess therein, an annular flange on the lower end of said sleeve, a bolt pivoted within said casing and arranged to extend through said opening, said shackle having 80 a notch therein disposed for alinement with said opening, said bolt arranged to fit within the notch and disposed at its free end normally above said first named flange and means for normally holding said bolt in extended position. 85

3. A lock comprising a casing, a shackle slideable in said casing and having notches adjacent each end, a sleeve mounted upon said shackle and disposed partly within said casing, a pair of bolts slideable and pivotally mounted within said casing and arranged to coöperate with said notches, said sleeve having an opening therein to receive one of the bolts, said opening arranged to aline with 90 one of the notches in said shackle whereby the bolt may engage said last named notch, and means for normally yieldingly holding said bolts in extended position. 95

In testimony whereof I affix my signature 100 in presence of two witnesses.

ULRICH REIDT.
